CLAIM

The ornamental design for a computer housing, as shown and described.

DESCRIPTION

FIG. 1 is a perspective view of a computer housing showing my new design with the lid closed;

FIG. 2 is a perspective view thereof with the lid shown opened;

FIG. 3 is a front elevational view thereof;

FIG. 4 is a top view thereof;

FIG. 5 is a rear elevational view thereof;

FIG. 6 is an elevational view of the one end thereof;

FIG. 7 is a bottom view thereof; and,

FIG. 8 is an elevational view of the other end thereof.

FIG. 1

FIG. 2

FIG. 3

FIG. 4

FIG. 5

FIG. 6

FIG. 7

FIG. 8
